UNITED STATES PATENT OFFICE.

ERNEST MOONEY, OF YORK, ENGLAND.

LUBRICATING DEVICE FOR RAILWAY VEHICLE AXLES.

Application filed January 27, 1927, Serial No. 163,981, and in Great Britain February 26, 1926.

This invention relates to that kind of railway axle lubricating device in which an absorbent pad connected to or formed integral with capillary feeders dipping into the oil 5 in the axle-box is supported in contact with the journal by means of a spring frame comprising a cradle, a transverse bearer strip central to the cradle, straight longitudinal side members connected together by transverse strips, and double elliptical side members attached to the longitudinal side members and to the ends of the transverse bearer strip.

In employing this type of lubricating device it has been found that the cradle member had a tendency to become wedged between the ends of the double elliptical side members when inserting the device as a whole into the axle box, with the result that 20 the pad only bears against one end of the journal and the other end is left unlubricated. Now the object of the present invention is to modify or improve the construction of this type of axle lubricating device 25 with a view to overcoming this disadvantage.

According to the invention the double elliptical side members of the spring frame are connected together by transverse members adapted to prevent the wedging of the 30 cradle between the ends of the double elliptical side members when the said cradle is depressed thereon.

In order that the invention may be clearly understood and readily carried into effect, 35 the same will now be more fully described with reference to and by aid of the accompanying drawings wherein:—

Figure 1 is a side elevation of my improved axle lubricating device.

40 Figure 2 is a plan view of Figure 1, but with a portion of the absorbent pad omitted for the sake of clearness.

Figure 3 is a side elevation showing the cradle depressed at one end.

45 Referring to the drawings, 1 is the absorbent pad formed integral with capillary feeders 2, adapted to dip into the lubricating oil in the axle box (not shown), said absorbent pad 1, being supported by means of a spring frame comprising a cradle 3, a transverse bearer strip 4 central to the cradle 3, straight longitudinal side members 5, and

double elliptical side members 6, attached to the straight longitudinal side members 5 and to the ends of the transverse bearer strip 4. 55

According to the invention, the double elliptical side members 6, have their ends connected together by transverse members 7, adapted, when the cradle 3 is depressed as 60 shown at Figure 3, to engage the end pad-supporting members of the cradle 3, and thereby prevent wedging of said cradle 3, between the ends of the double elliptical side members 6. The transverse members 7, are 65 secured to the ends of the double elliptical side members by rivets 8, and said transverse members 7 are made of flexible strip metal similar to that employed for the other members of the spring frame. It will, of course, 70 be understood that any other appropriate means for securing the transverse members 7, to the ends of the double elliptical side members 6 may be employed. 75

I claim:—

1. In a lubricating device of the class described, an absorbent pad, a yieldable frame supporting said pad, said frame comprising a cradle, side members, elliptical members connected to said cradle and said side members, and means extending transversely of the frame and connected to said elliptical members to prevent the wedging of the cradle between the elliptical members when the device is depressed. 80

2. In a lubricating device of the class described, an absorbent pad, a yieldable frame supporting said pad, said frame comprising a cradle, spaced longitudinally disposed side members, elliptical members connected to 90 said cradle and said side members, and transversely disposed members connected to the ends of said elliptical members to prevent the wedging of the cradle between the elliptical members when the cradle is depressed. 95

3. In a lubricating device of the class described, an absorbent pad, a yieldable frame supporting said pad, said frame comprising a cradle, spaced longitudinally disposed side members, a pair of elliptical members connected to said cradle and said side members, and having substantially horizontal end flanges, transverse bars positioned between said flanges and connected thereto for pre- 100

venting the wedging of the cradle between the elliptical members when the cradle is depressed.

4. In a lubricating device of the class described, an absorbent pad, a cradle supporting said pad, spaced longitudinally disposed side members beneath said cradle, double elliptical members connected to said cradle

and said side members, elliptical members terminating in substantially horizontal opposed flange portions, transverse members connected to said portions for preventing the wedging of the cradle between the ends of the elliptical members when the cradle is depressed. 10

ERNEST MOONEY.
